TAPE DRIVING SYSTEM FOR MAGNETIC
SOUND RECORDING MACHINES AND THE
LIKEHomer G. Tasker, Van Nuys, Calif., assignor to
Herman S. Heller, West Los Angeles, Calif.

Application October 24, 1940, Serial No. 362,701

4 Claims. (Cl. 242—55)

This invention relates generally to driving systems for magnetic sound recording machines and the like employing record tape. The invention is herein described principally as a drive system for a record tape of the magnetic type of sound recording and reproducing machine, though without necessary limitation thereto.

The record tape of magnetic sound recording machines is commonly fed from a supply reel, is driven by a constantly driven drive pulley, and is taken up by a take-up reel. In prior sound recording machines, two or more shafts have been required for these reels and drive pulley, necessitating certain interconnecting gear. Over-running clutches have sometimes been provided, in such arrangement in the driving gear between the drive motor and the reels as to drive selectively the reel acting as take-up reel for the direction the tape is then being driven by the drive pulley.

A general object of the present invention is the provision of a tape driving system of increased compactness, in which both reels as well as the constant speed drive pulley are mounted on a single shaft, so as to do away with all gearing for interconnection between a plurality of shafts.

A further object is the provision of an improved and more compact arrangement of the over-running clutches employed for the purpose of selectively driving the take-up reel.

In accordance with the invention in its present preferred form, the tape drive pulley is mounted tightly on the single drive shaft, adapted to be driven in either direction by a reversible drive motor. The two reels are also mounted on this same drive shaft, and the over-running clutches are contained within the hubs of said reels, the arrangement being such that for one direction of rotation of the single drive shaft, one of the reels will be driven and the other will idle, and for the reverse direction of rotation of the drive shaft, the second mentioned reel will be driven and the first mentioned reel will idle. The tape is guided from one reel into the plane of the drive pulley, passes over the drive pulley and through the translating magnets while in said plane, and is then guided into the plane of and wound on the other reel. The arrangement is very simple and compact, and provides a tape drive system characterized by exceptional smoothness of action and uniformity of tape travel past the translating magnets.

The invention will be best understood from the following detailed description of a present illustrative embodiment thereof, reference for

this purpose being had to the accompanying drawings, in which:

Fig. 1 is an elevation of a recording machine in accordance with the invention;

Fig. 2 is a horizontal section taken on line 2—2 of Fig. 1;

Fig. 3 is a section taken in accordance with line 3—3 of Fig. 2;

Fig. 4 is a section taken on line 4—4 of Fig. 3; and

Fig. 5 is a section taken on line 5—5 of Fig. 2.

Numeral 10 designates generally a supporting panel, typically, though not necessarily, arranged in a vertical plane. Mounted on the back of this panel 10 is a reversible electric drive motor 11, on one end of which is mounted a right angle drive 12 from which projects a motor driven drive shaft 13, the latter projecting through panel 10 as illustrated. Shaft 13 is drivingly connected to a shaft 14 that carries a driving pulley 15 and a pair of reels 16 and 17, the pulley being tightly mounted on shaft 14, and being located between the reels and panel 10, all as clearly illustrated in Fig. 2. In the specific illustrative embodiment of the invention here shown, shaft 14 is hollow and receives the end portion of shaft 13, being provided with slots 20 at its inner end receiving a transverse pin 21 carried by shaft 13. Shaft 14 is thus positively clutched to shaft 13.

Shaft 14 has an enlarged rearward portion 22 on which is press fitted a flanged bushing 23 and a washer 24 which define an annular channel 25 that receives a complementary bearing ring 26, the latter being held within a retainer ring 27 secured to panel 10 as by screws 28. Shaft 14 with bushing 23 and washer 24 thus turn freely within bearing member 26.

The hub 30 of the aforementioned tape driving pulley 15 is tightly mounted on shaft 14 immediately adjacent shoulder 31 formed between shaft 14 and its enlarged rearward portion 22. Immediately forwardly of pulley 15 are the two reels 16 and 17, which have driving engagement with the shaft through over-running clutches contained within their hubs, as presently to be described. Each of these reels embodies a pair of tubular hub members 40 and 41, which together define an annular space 42 surrounding shaft 14, and which are formed with engaging peripheral annular flanges 43, to which are secured reel flanges 44, the flanges 43 and 44 being secured together as by means of the socket and screw elements 45 and 46. The two flanges 43 space the reel flanges 44 properly for the tape T.

which is wound around the periphery of the flanges 43, as will readily be understood from an inspection of Fig. 2.

Enclosed and relatively rotatable in the annular space 42 defined by hub members 40 and 41 is a clutch disk 50 having a central bore 51 which receives shaft 14 with free rotative fit. Mounted in angularly disposed cavities or recesses 52 formed in disk 50 and opening inside bore 51 are rollers 54 which engage shaft 14 (see Fig. 1). The rollers 54 are yieldingly urged into engagement with shaft 14 by means of resilient elements such as felt pads 55 placed in recesses 52 in back of the rollers. The rollers are retained in position by means of a retainer plate 55' mounted in a countersink in the side of disk 50. The described elements form a simple and effective over-running or roller ratchet clutch. The over-running clutches for the two reels will be understood to be identical except that the angular direction of the clutch roller slots or recesses 52 for the two clutches will be understood to be in reversed aspect, right for left, so that rotation of shaft 14 in a left-handed direction as viewed in Fig. 1 causes rollers 54 of the clutch contained within the hub of reel 17 to engage the shaft, so as to drive reel 17, while for right-handed rotation of shaft 14, the rollers 54 of the clutch contained within the hub of reel 16 will drivingly engage the shaft so that reel 16 is then driven. Of course, reel 16 idles when reel 17 is being driven with left-handed rotation of the shaft, and reel 17 idles when reel 16 is being driven with right-handed rotation of the shaft.

The rotation of clutch disks 50 is imparted to the reel through pairs of buttons or pads 60, preferably formed of some such material as fibre or Micarta, which are mounted in holes 61 extending through the disk and are pressed outwardly against the inside surfaces of hub members 40 and 41 by means of springs 62. There may be several such pairs of pads 60 spaced about the hub of the reel, as will be understood. The spring-pressed pads 60 provide a yielding or slipping frictional or driving connection between the sides of the disk and the hub of the reel, so that the slippage made necessary by the fact that the roll of tape on the reel is of greater diameter than the drive pulley 15, and hence must rotate more slowly than the drive pulley, may take place at this point.

A slight frictional drag is preferably applied to each reel, in order to prevent the reel from over-running while it is idling on its shaft, or in other words, while it is acting as the feed reel, and also to promote quick stopping of both reels when the drive shaft stops. In the present illustrative embodiment of the invention, this frictional drag is provided by parts of or elements mounted on a pair of magazines 10 provided for the two reels. These magazines 10 each comprise circular side wall portions 71 and 72 having overlapping peripheral portions 73 and 74, respectively. The side walls 71 and 72 of each container have central openings 75 which receive tubular bosses 76 and 77 projecting from the two hub members 40 and 41, and the side walls 71 and 72 have inwardly indented portions 78 immediately around apertures 75 adapted to bear against the sides of hub members 40 and 41. Preferably, in order to increase the frictional effect, hub members 40 and 41 are faced with fibre disks 79. Additional friction means in the form of friction shoes 79', of fibre or the

like, are preferably mounted on spring arms 80 secured to the walls 72 of the magazines, and are arranged to bear on the fibre-faced sides of the reel hubs, as clearly illustrated in Fig. 2.

5 The pressure exerted by these shoes is adjustable by means of screws 81 passing through container walls 72 and having screwthreaded engagement with the arms 80, in the arrangement clearly shown in Fig. 2. It will be evident 10 that rotation of screws 81 will flex arms 80 in such a way as to adjust the frictional pressure exerted by shoes 79 against the hubs of the reels. These frictional effects, as stated hereinabove, 15 apply a slight drag to the reels, and thus prevent them from over-running while acting as supply reels, as well as causing them to stop more or less abruptly when the drive shaft stops.

The outside bosses 77 of the two reel hubs are preferably formed with slots such as 84, enabling the hubs to be engaged and turned by a 20 suitable spanner wrench as an aid in removing the reels from shaft 14.

As here shown, the two reel containers 10 are mounted in face to face contact and are 25 positioned against brackets 90 secured to panel 10. Releasable clamp arms 91, pivoted on brackets 90, as at 92, extend outwardly in contact with the peripheries of magazines 10, and have at their ends inwardly bent portions 93 engaging 30 over the magazines as clearly illustrated in Fig. 2. Extensions 94 from arm 91 are engaged by springs 95 mounted on brackets 90, which springs are arranged to yieldingly support the clamp arms in the clamping position of Fig. 2, 35 but to permit outward movement of the clamp arms to clear the magazines when the latter are to be removed from the drive shaft, all as will be clear from an inspection of Fig. 2.

In order to prevent rotation of the magazines 40 70, portions of the outside peripheral flange 74 of each magazine are severed and rolled outwardly, as indicated at 100, so as to receive between them opposite edges of one of the clamp arms (see Fig. 5).

45 Apertures 102 adapted to pass tape T are formed in the peripheral portions of the magazines, as indicated in Fig. 1.

The two ends of tape T may be anchored to the reel hubs in any suitable or conventional manner, though Fig. 1 shows one simple and convenient arrangement, in accordance with which the end of the tape is provided with an enlarged portion 103 adapted to be received transversely into a socket or drill hole 104 extending inwardly through the inner portion of a reel flange 44 and through hub flanges 43, an angular slot 105 connecting said hole 104 with the peripheral hub surface defined by the outer edges of hub flanges 43.

60 In accordance with the particular tape threading arrangement here illustratively shown, the tape is wound right-handedly on outside reel 17 and left-handedly on inside reel 16. From outside reel 17 the tape is threaded over angularly positioned pulleys 110 and 111, which convey the tape to a plane to the rear of the two reels and in alignment with tape driving pulley 15. The tape then passes over the top side of tape driving pulley 15 (see Fig. 3), then passes in a substantially horizontal direction to and under a tensioning pulley 112, and from there passes upwardly to and around an idler pulley 113, the latter being mounted near the top of panel 10. From idler pulley 113 the tape passes straight

70 downwardly to and around a similar idler pulley 75

114 immediately under pulley 113 but positioned near the bottom of panel 10. The tape next travels upwardly in an angular direction to and over a tensioning pulley 115, located immediately below tensioning pulley 112, and from there travels back in a substantially horizontal direction to pass over the lower side of drive pulley 15. The tape next passes to and around an angularly positioned idler pulley 116, which takes it to the plane of inside reel 16, the tape then being wound onto reel 16 as indicated in Fig. 2.

The above mentioned idler pulley 113 is furnished with a pair of spring urged retaining rolls 120 which bear on the tape passing over the pulley 113, and the pulley 114 is equipped with a single spring urged retaining roller 121 which engages the tape as it passes over pulley 114.

The tensioning rollers 112 and 115 are mounted on a stud 126 screwed into panel 10, the arms 124 and 125 being received between a shoulder 127 presented by a hexagonal flange 128 formed integrally with stud 126, and the large flat head 129 of a screw 130 screwed into said stud, friction washers 131 separating the two arms from one another and separating the arms from flange 128 and head 129, all as will be clear from inspection of Fig. 4. The two arms 124 and 125 are interconnected by tension spring 135 which serves to urge the two rollers 112 and 115 into tensioning engagement with the tape, while a tension spring 136 connected between upper arm 124 and an anchor pin 137 set into panel 10 counteracts the effect of gravity on the arms and rollers.

A pair of retaining rollers 140 are mounted on the arms of a yoke shaped plate 141 and are adapted to be supported by plate 141 in a position to hold the tape in driving engagement with pulley 15. Plate 141 has an extension 142 surrounded by a compression spring 143 and having pivotally mounted on its rearward end a cam 145 having a projecting pin 146 by which it may be conveniently manipulated. The periphery of cam 145 is adapted to be brought to bear against a stationary bracket 150 secured to panel 10, said bracket being provided with an aperture 151 that slidably passes the extension 142 of yoke plate 141. One end of spring 143 bears against one side of this bracket 150 and the other end of said spring bears against the plate 141, which has an offset at 154 and outwardly extending ears 155 to receive the pressure of said spring. It will be understood that rotation of cam 145 will draw yoke plate 141 and the retaining rollers 140 rearwardly and out of engagement with the tape on drive pulley 15, but that when cam 145 is in the position of Fig. 3, yoke plate 141 is being urged in the direction of pulley 15 by the pressure of spring 143, and that retaining rollers 140 are therefore in pressural engagement with the tape on the periphery of pulley 15.

The vertical stretch of tape between the two idler pulleys 113 and 114 passes between the two halves of a translating magnet head R, which may be of any suitable or usual construction, and need not be detailed herein.

The operation of the tape driving system of my invention is as follows: Rotation of drive shaft 14 in a right-handed direction causes the over-running clutch contained within the hub of inside reel 16 to grip the shaft, so that clutch disk 50 turns right-handedly with the shaft, and, through spring urged pads 60, applies a frictional drive tendency in a right-handed direction to the hub of reel 16. At the same time, reel

17 will simply idle on the shaft. The tape then travels from reel 17 over the top side of drive pulley 15, through the translating magnet head, over the underside of drive pulley 15, and finally onto inside reel 16 which is being driven as above described. The diameter of the roll of tape on reel 16 being always greater than the diameter of drive pulley 15, the reel tends to take up the tape faster than it arrives from the drive pulley. Accordingly, slippage takes place between the positively driven clutch disk 50 and the hub of the reel at the points where the spring pressed friction pads 60 drivingly engage the hub. There is thus an over-drive tendency on the reels, but the reels are held back to a speed determined by the rate of arrival of the tape. The idling reel 17 is at this time being prevented from over-running by the frictional effect of the indented portions 77 of the magazine on the sides of the hub, and also by the frictional pressure of shoe 79 on the hub. These frictional effects are preferably made sufficient that the idling reels will stop more or less abruptly when drive shaft 14 is stopped. For the reverse direction of rotation of shaft 14, operations are similar, except that the tape on this instance travels from inside reel 16, then idling and serving as supply reel, to outside reel 17, which is then driven and serves as take-up reel. The two movably mounted tape tensioning pulleys 112 and 115 act constantly to maintain the tape properly taut between the drive pulley 15 and the pulleys 113 and 114 at the two ends of translating magnet units R.

My preferred form of drive embodies the feature of a tape driving pulley and two reels, each containing an over-running clutch, all mounted on a single drive shaft, the pulley being tightly mounted on the shaft, and the reels being alternately clutched to the shaft as the shaft turns in one direction and then the other. However, certain features of my invention are not limited to a concentric arrangement of reels and drive pulleys. For instance, it is not indispensable to the invention, even though highly desirable, that the drive pulley 15 be mounted on the same shaft or axis with the reels. Thus even without the desirable feature of concentricity between reels and drive pulleys, great advantage, compactness and simplicity results from the incorporation of the over-running clutches inside the hubs of the two reels. Moreover, it is not indispensable to the invention in the aspect of the provision of over-running clutches inside the reel hubs that the two reels be mounted in concentric relation on a single shaft, and certain of my claims are accordingly made to the provision of an overrunning clutch within the hub of a reel, irrespective of the relative arrangements of the other reel or of the remainder of the tape driving system.

I have now shown for illustrative purposes one present specific form of my invention; it will be understood, however, that this is for illustrative purposes only, and that various changes in design, structure and arrangement may be made without departing from the spirit and scope of my invention or of the appended claims.

I claim:

1. In a record tape driving means for a sound recording and/or reproducing machine, the combination of a drive shaft, a smooth periphery tape engaging tape drive pulley on said drive shaft, a pair of reels relatively rotatable on said drive shaft, means for guiding and supporting

the tape between said reels to pass in driving contact with two points of said pulley, means for tensing the tape between said points of contact and over-running clutches for said reels adapted and arranged to clutch the reels to the shaft alternately as the drive shaft is driven in reverse directions.

2. In a record tape driving means for a sound recording and/or reproducing machine, the combination of a drive shaft, a tape engaging tape drive pulley on said drive shaft, a pair of reels relatively rotatable on said drive shaft, means for guiding the tape to pass in peripheral driving contact with said pulley between said reels, each of said reels embodying a hollow reel hub and a pair of reel flanges for a record tape, over-running clutch disks surrounding the shaft within the hollows of said reels, ratchet rollers carried by said disks and adapted to clutch said disks to the shaft with opposite directions of rotation of the shaft, and friction elements projecting from the sides of the disks into frictional driving engagement with the hubs.

3. In a record tape driving means for a sound recording and/or reproducing machine, the combination of a drive shaft, a tape engaging tape drive pulley on said drive shaft, a pair of reels

relatively rotatable on said drive shaft, means for guiding the tape to pass in peripheral driving contact with said pulley between said reels, each of said reels embodying a hollow reel hub and a pair of reel flanges for a record tape, over-running clutch disks surrounding the shaft within the hollows of said reels, ratchet rollers carried by said disks and adapted to clutch said disks to the shaft with opposite directions of 10 rotation of the shaft, and spring pressed friction pads on the sides of the disks frictionally drivingly engaging the hubs.

4. In a record tape driving means for a sound recording and/or reproducing machine, the combination of a drive shaft, a smooth periphery tape engaging tape drive pulley on said drive shaft, a pair of reels relatively rotatable on said drive shaft, over-running clutches for said reels adapted and arranged to clutch the reels to the 20 shaft alternately as the drive shaft is driven in reverse directions, tape guide means for guiding the tape between the two reels and two spaced arcs of peripheral contact with the tape drive pulley and means for tensing the tape between 25 said arcs of contact.

HOMER G. TASKER.
